UNITED STATES PATENT OFFICE.

WALTER S. MAYER, OF PHILADELPHIA, PENNSYLVANIA, ASSIGNOR TO THE MACHEN & MAYER ELECTRICAL MANUFACTURING COMPANY, OF PHILADELPHIA, PENNSYLVANIA, A CORPORATION OF NEW JERSEY.

ELECTRIC SNAP-SWITCH.

No. 892,670.

Specification of Letters Patent.

Patented July 7, 1908.

Application filed January 2, 1907. Serial No. 350,328.

To all whom it may concern:

Be it known that I, WALTER S. MAYER, a citizen of the United States, residing in the city and county of Philadelphia, State of Pennsylvania, have invented certain new and useful Improvements in Electric Snap-Switches, of which the following is a specification.

My invention relates to an improvement in electric snap switches, and it has for its object to provide a switch of this character combining efficiency and simplicity.

My invention resides in the combination and arrangement of parts as hereinafter described in detail, set forth in the claims, and as illustrated in the accompanying drawings, in which

Figure 1 is a top plan view of a switch embodying my invention, with the cover and switch button shown in Fig. 3 removed; Fig. 2 is a section on the line 2—2 of Fig. 1, certain portions of the device being shown in side elevation; Fig. 3 is a view at right angles to the line on which Fig. 2 is taken; Fig. 4 is a top plan view showing certain details of construction, certain portions of the switch being broken away; Fig. 5 is a side elevation of the portion of the switch shown in Fig. 4; Fig. 6 is an edge view of one of the contact brushes; Fig. 7 is a top plan view of the same; Fig. 8 is a side elevation looking towards the bottom portion of Fig. 7; Fig. 9 is a top plan view of a stop plate; and Fig. 10 is an edge view of the same.

In the drawings,—1 designates the base portion of an electric snap switch, which portion of any suitable insulating material, as, for instance, porcelain. The central portion of this base is provided with a depression in which is located a stop plate 2, which is of metal and is rectangular in general outline. At each of the corners, portions of the plate are cut away so as to form seats 3, the said seats being slightly inclined, as indicated, so that they are deeper at their outer ends than at their inner ends. 4 designates shoulders, one of which is located at one end of each of the said seats, and 5 designates inclined or beveled edges leading from the shoulders to the adjacent edges of the plate 2. The plate is provided with a central perforation or opening 8 through which one end of a shaft 9 is projected, the said shaft being also projected

through a perforation or opening 10 in the bottom of the insulating base portion 1. 15 designates a nut having screw-threaded engagement with the lower end of the shaft 9 and by means of which the said shaft is secured in position to the said base portion 1.

20 designates a trigger or shifter (consisting, in the construction shown, of a plate) which is pivotally secured at 21 to a plate 22. The latter plate is secured to a plate 23 having projecting contact arms 24. The plates 22 and 23 are insulated from each other by 65 means of the insulating blocks 25 and 26. The plates 22 and 23 are mounted upon and adapted to rotate about the shaft 9. The shifter 20 is provided with a laterally extending stop projection 30, which is adapted to 70 engage and rest upon the seats 3 of the stop plate 2. The said shifter is also provided with a projection 31 located adjacent to the point of its pivotal connection to the plate 22, as particularly indicated in Figs. 1 and 4. 75 of the drawings. The said projection 31 is adapted to be engaged by one end of a spring 35 which is coiled around the shaft 9, the other end of the said spring being in engagement with a collar or plate 36, rigidly secured to the said shaft 9.

38 designates a switch button connected to the upper or outer end of the shaft 9. The shifter 20 is provided with an eccentric opening 40.

41 designates a lever which is rigidly connected to the shaft 9, the end of which lever is adapted to contact with the shifter 20 at a point within the said eccentric opening 40.

In order to prevent rotation in one direction of the said lever 41 and the shaft connected thereto with respect to the said shifter 20, I have provided a shoulder 42 upon the said shifter with which one side of the lever 41 is normally in engagement. 90 When the shaft is turned in the direction in which the hands of a watch travel by any means, as, for instance, the switch button 38, the lever 41 engages with the shifter 20 so as to move the same outwardly in the same 100 direction upon its pivot 21, thus occasioning movement of the lateral stop projection 30 out of engagement with any one of the seats 3 within which it happens to be seated. Movement of the shifter 20 in the direction 105 opposite to that of the hands of a watch is

prevented by reason of the fact that the projection 30 is in contact with a shoulder 4 at one end of a seat 3. The shaft 9 and the lever 41 connected thereto may be regarded 5 and designated as a controller, since it is through these members that the trigger or shifter 20 is disengaged from the seats 3 upon the stop device 2.

When the lateral projection 30 is moved 10 out of engagement with one of the seats 3, the spring 35, which has been placed under tension by reason of the turning of the said shaft while one end of the said spring, namely, that which is in engagement with 15 the projection 31, is held against movement, occasions a quick movement of the shifter forward to the next seat which it engages by reason of the fact that in moving to this position, the lever 41 is brought into the same 20 relative position with respect to the shifter 20, as is indicated in Fig. 4 of the drawings. The relative arrangement of the shifter 20 with respect to the several seats 3 upon the stop plate 2 and with respect to the lever 41 25 is such that the said lever 41 and the shaft 9 are turned or twisted through a distance somewhat greater than 90° so that when the said shifter 20 moves forward into position upon a succeeding seat, the said shaft and 30 lever 41 are rotated short distances rearwardly so as to bring the lever 41 into contact with the shoulder 42. If this were not the case and the lateral stop projection 30 escaped from one of the seats 3 before the 35 lever 41 had traveled over an arc greater than 90°, the said shifter 20 would be snapped forward by reason of the untwisting of the spring 35 so as to cause the shoulder 42 to strike with considerable force against the 40 side of the said lever 41.

50 designates the binding posts having central perforations, and which posts are connected to plates 51, which are in turn connected to the base portion 1 of the device. 45 53 designates binding screws by means of which the incoming and outgoing line wires are electrically connected to the binding posts.

55 designates spring contact brushes which 50 may be described as being of U - shape. These brushes are each provided with openings, as indicated at 56, the purpose of such openings being to secure a maximum amount of resiliency and flexibility of the brushes 55 with a minimum amount of metal.

In the construction shown, the binding posts 50 project through the openings 56. The back portions 57 of the U-shaped contact brushes, which portions connect the opposite sides or legs of the said brushes together, are connected to projections 58 extending upwardly from the plates 51. By securing the brushes in place by connecting their bridge portions or extreme outer ends 60 to suitable supports, as is indicated in the 65

drawings, at points adjacent to or near the outer edge of the base portion 1, I am enabled to employ brushes having spring plates of relatively great length, but which, however, do not extend too far in towards the 70 center of the device, that is, the center of the base portion.

It will be observed that the contact arms 24 extending outwardly from the plate 23 are adapted to pass between the opposite 75 spring plates or legs of the contact brushes and to be engaged upon their opposite sides by the respective spring plates. In order to insure that the contact arm shall pass in between the said legs, the edges thereof are 80 flared outwardly, as indicated at 60 in Fig. 2 of the drawings.

Having thus described my invention, I claim:

1. In a device of the character described, 85 the combination of a stop device provided with seats, a rotatable shaft, a plate loosely mounted upon the said shaft, contact arms rigidly connected to the said plate, a shifter pivotally connected to the said plate and 90 adapted to engage any one of the seats upon the said stop device, and the said shifter having a laterally extending projection situated between the pivotal connection between the shifter and plate and the said shaft, a 95 spring surrounding the said shaft, one end of the said spring being connected to the said shaft and the other end engaging the said projection, a lever connected to the said shaft and adapted to move therewith, the 100 said lever being in engagement with the said shifter and adapted to occasion movement of the said shifter to disengage the same from any one of the said seats.

2. In a device of the character described, 105 the combination of a base portion or member, a stop device secured to the said member, contacts supported upon the said member, a rotatable shaft extending through the said stop device and connected to the said 110 member, a plate loosely mounted upon the said shaft, contact arms loosely mounted upon the said shaft and rigidly connected to the said plate, said arms being adapted to engage the said contact brushes, a shifter pivotally connected to the said plate, the said 115 shifter being adapted to engage any one of the seats upon the said stop device, and the said shifter having a laterally extending projection situated between the pivotal connection 120 between the shifter and plate and the said shaft, a spring coiled around the said shaft, one end of which is connected to the said shaft and the other end of which is in engagement with the said projection the said 125 spring occasioning movement of the shifter to engage the said seats, a lever rigidly secured to the said rotatable shaft, which lever is in engagement with the said shifter and is adapted to occasion movement of the same 130

about its pivot to occasion its disengagement from any one of the seats upon the said stop plate.

3. In a device of the character described, the combination of a controller, contact devices, a shifter operatively connected to the said contact devices, the said shifter being provided with a shoulder with which the said controller is adapted to contact, and energizing means associated with the said controller and contacting with a portion of the shifter situated between the point of connection between the shifter and the said contact devices and a member of the controller to occasion movement thereof around and transversely of the said member of the controller to engage seats upon a stop device, and the stop device provided with seats, the said stop device being also provided with shoulders at one end of each of the said seats to prevent movement of the shifter in one direction.

4. In a device of the character described, the combination of a controller, contact devices associated with the said controller, a shifter operatively connected to the said contact devices, the said shifter being provided

with a projection and also with a shoulder with which a member of the said controller is adapted to contact to prevent movement in one direction with respect to the said shifter, an energizing device connected to the said controller and being in contact with a portion of the said shifter, the said portion being situated between the connection between the shifter and the contact devices and the said member of the controller, a stop device having seats adapted to receive the said projection upon the shifter, and the said stop device also having shoulders at one end of the said seats against which the said projection is adapted to contact to prevent movement of the said shifter in one direction, and the said seats being respectively inclined so that they are deeper at their outer ends than at their inner ends.

In testimony that I claim the foregoing as my invention, I have hereunto signed my name this 26th day of December A. D. 1906.

WALTER S. MAYER.

In the presence of—

HARRY F. AMBLER,
LAURA KLEINFELDER.
